DESIGN FOR A COMBINED BOTTLE AND CAP

Charles H. Burger, New York, N.Y., assignor to
Dermetics, Inc., New York, N.Y.

Application April 5, 1946, Serial No. 128,469

Term of patent 14 years

(Cl. D58—8)

To all whom it may concern:

Be it known that I, Charles H. Burger, a citizen of the United States, residing at New York, in the county of Bronx and State of New York, have invented a new, original, and ornamental Design for a Combined Bottle and Cap, of which the following is a specification, reference being had to the accompanying drawing, forming part thereof, wherein—

Fig. 1 is a side elevational view;

Fig. 2 is a top plan view, and

Fig. 3 is an end view of a combined bottle and cap, showing my new design.

I claim:

The ornamental design for a combined bottle and cap, as shown.

CHARLES H. BURGER.
